UNITED STATES PATENT OFFICE.

WESLEY HYRE, OF STROH, INDIANA.

HARROW.

No. 880,998.

Specification of Letters Patent.

Patented March 3, 1908.

Application filed September 17, 1907. Serial No. 393,378.

To all whom it may concern:

Be it known that I, WESLEY HYRE, citizen of the United States, residing at Stroh, in the county of Lagrange and State of Indiana, have invented certain new and useful Improvements in Harrows, of which the following is a specification.

This invention has for its object an improved tractor-actuated harrow, and the invention consists in certain constructions and arrangements of the parts that I shall hereinafter fully describe and claim.

For a full understanding of the invention reference is to be had to the following description and accompanying drawings, in which:

Figure 1 is a side elevation illustrating my improved harrow and traction engine to which it is connected; Fig. 2 is a top plan view thereof; and, Fig. 3 is a front elevation of the traction engine employed.

Corresponding and like parts are referred to in the following description and indicated in all the views of the drawings by the same reference characters.

The traction engine shown in connection with my harrow embodies rear traveling wheels 1, front traveling wheels 2, and a main framework 3 supported by said wheels. The framework 3 comprises the two longitudinally extending I-beams 4 which are provided with forwardly converging portions 5 to which the rear ends of the arched bars 6 are connected. These bars 6 meet at their forward ends and are supported on a steering post 7 of the front traveling wheels, said post being journaled in the upper end of the transversely arched yoke 8 supported on the shaft of the front traveling wheels 2. A toothed segment 9 is secured by the angle bars 10 to the yoke 8 and lies in a horizontal plane as shown with its teeth facing rearwardly, the said teeth of the segment meshing with a pinion 11 secured on the lower end of the vertically extending steering rod 12. This rod is journaled in a bearing secured to the foremost one of three transversely extending I-beams 13 forming parts of the main framework 3, and said steering rod is provided at its upper end with a hand wheel 14.

15 designates a guide member for the segment 9, said member being suspended from the bars 16 riveted or otherwise secured to the arched bars 6 and abutting against the

upper face of the segment, so as to hold the same in a true horizontal plane.

The vehicle may be propelled by any desired form of steam or gasoline engine, or other prime mover, the same being omitted from the drawings as it is no part of the present invention. The driving shaft of such engine may be connected to the countershaft 17 by the sprocket 18 or similar gearing. The shaft 17 is journaled in two intermediate longitudinal I-beams 4^a forming parts of the framework and connected at their front ends to the brace bars 19, said bars being connected in turn to the arched bars 6, as clearly illustrated in the top plan view of the drawings. The shaft 17 carries sprockets 20 at its ends, said sprockets being connected by the sprocket chains 21 with the chain wheels 22 secured by clips or any other suitable fastening devices to the respective rear traveling wheels 1.

23 designates tensioning idlers for the chain.

My improved harrow is arranged aslant as shown, and the disks 30 thereof will all cut the same way, side draft being eliminated by the weight of the traction engine. The disks 30 are mounted on a shaft 31 which is journaled in the laterally tapering framework 32. This framework is provided at its ends with vertical braces 33 and oblique braces 34, the latter forming parts of or connected to the trailing arms 35 that are swung from the outer ends of the main axle 1^a.

In order to raise and lower the harrow, the rear cross bar of the harrow frame 32 is provided with an eye 36 receiving the hooked end of a link rod 37. The upper end of this rod is connected to one arm of a bell crank lever 38 fulcrumed on the rear transverse I-beam 13^a of the framework 3. To the other arm of the lever, a link 39 is connected, said link being also connected at its front end to the hand lever 40 arranged for locking engagement with the quadrant 41. Obviously, by manipulating the lever 40, the harrow may be raised and lowered.

42 designates a chain which may assist in supporting the harrow in its proper position and which is designed to engage a hook 43 secured to the rear cross bar 13^a of the framework.

Although, not forming a part of the present invention, I have illustrated in connec-

tion with the traction engine, a scraping or grading blade 24. Rods 25 are secured to the blade 24 and extend upwardly through bearings in the framework and said rods are connected together at their upper ends by means of a cross bar 26, as shown. Pending links 27 are secured at their lower ends to the cross bar 26 and at their upper ends to the arms of the actuating lever 28. This lever is fulcrumed intermediate of its ends on a standard 29 rising front the framework 3. By manipulating the lever 28, the scraping or grading blade may be raised or lowered, as desired, and when not in use 15 may be held in an inoperative elevated position.

Having thus described the invention, what is claimed as new:

A machine of the character described, 20 comprising a supporting framework, travel-

ing wheels upon which said framework is mounted, said framework embodying a rear cross bar, arms swinging on the outer ends of the axle for the rear traveling wheels and trailing behind the same, a transversely 25 tapered harrow frame secured to the rear ends of said trailing arms, a shaft mounted in said frame, disks secured to said shaft, a bell crank fulcrumed on the rear cross bar of the main supporting framework, a hand 30 lever having an operative connection with said bell crank and mounted on the framework, and a link connecting one arm of said lever with the harrow frame.

In testimony whereof I affix my signature 35 in presence of two witnesses.

WESLEY HYRE. [L. S.]

Witnesses:

GEORGE E. MILLER,
MONROE F. WRIGHT.
